ATTORNEY

UNITED STATES PATENT OFFICE

HAZEL HIGGINS COX, OF NEW YORK, N. Y.

BRASSIÈRE

Application filed November 20, 1928. Serial No. 320,567.

This invention relates to garments, and in particular to a bust supporter or brassière.

An object of the present invention is to provide an improved form of combined girdle and bust supporter closely associated together of extremely light material adapted to closely fit and support the busts by means of straps extending over the shoulders of the wearer.

10 Another object of the invention is to provide a light girdle and bust supporter preferably of net material having a belt or girdle portion adapted to extend about the wearer just below the busts and formed integrally with bust enclosing and supporting portions closely fitting the busts, the belt or girdle portion being extended rearwardly to completely encircle the wearer.

Another object of the invention is to provide 20 a brassière having bust supports made up of a plurality of sections or gores preferably of net material, three gores of special form being used to form a cup-like support enclosing each bust, the gores being stitched together and to a spacing member at the front central portion of the garment, and to the belt sections at their opposite ends. And finally 25 it is another object of the invention to provide a plurality of straps joined at spaced points to the upper edge of each bust enclosing portion, the straps from each bust support being joined together in front of the shoulder and attached at the back to the rear portions of the girdle.

30 With these and other objects in view my invention includes the features of construction set forth in the following specification and illustrated in the accompanying drawing.

In the accompanying drawing annexed 40 hereto and forming a part of this specification, I have shown my invention embodied in a simple form of bust support and girdle of net material, but it will be understood that the invention can be otherwise embodied, and 45 that the drawing is not to be construed as defining or limiting the scope of the invention, the claim appended to this specification being relied upon for that purpose.

In the drawing—
50 Fig. 1 is a front view of the improved form

of garment shown in position upon a wearer;

Fig. 2 is a plan view of the garment shown apart from the wearer;

Fig. 3 is a view of the individual members or gores forming the girdle and bust supports 55 shown in the position assumed when the garment is ready to be stitched together.

In the above mentioned drawing I have shown but one embodiment of the invention which is now deemed preferable, but it is to 60 be understood that changes and modifications may be made within the scope of the appended claim without departing from the spirit of the invention.

Referring more in detail to the figures of 65 the drawing, I provide an improved garment, preferably of net material, adapted to form a girdle portion and bust support. The bust supporting portions of the garment comprise three principal gores 10, 11 and 12, 70 adapted to be stitched together along the dot and dash lines as indicated in Fig. 3, at 13—13 and 14—14. The front adjacent edges of the gores 10 and 11 are attached to a central spacer member 15 which properly spaces 75 the gores 10, 11 and 12 to properly fit the form of the wearer. It will be understood that the disposition of the gores will be reversed upon opposite sides of the garment. The opposite or outer ends of the gores 10 and 80 12 are attached to side or belt members 16 adapted to extend about the back of the wearer and be joined together by any suitable fastening means 17, shown in Fig. 2.

The three gores 10, 11 and 12 forming each 85 of the bust supports comprise an upper elongated gore member 10 with a downwardly curved lower edge. This curved edge is attached throughout its length to the upper curved edges of the two lower gore members 90 11 and 12. The lower gore members 11 and 12 have concaved confronting edges stitched together so that with these two seams 13 and 14 stitched together a pocket or bust supporting portion of the garment is completely 95 formed and adapted to closely fit over and enclose and support the bust.

It will be noted that the lower gore members 11 and 12 at their edges 14, which are 100 stitched together are oppositely curved rela-

tively to each other so that when the seam formed by joining these edges 14 is stitched the lower portions of the lower gore members will form a substantial girdle like portion 18 for the garment extending just below each bust and under the arms of the wearer. Above this girdle portion of the gores 11 and 12 is formed the lower portion of the bust support which encloses and supports the lower portion of the bust. These upper portions of the gores 11 and 12, together with the upper gore 10 substantially enclose the bust and support it with the aid of the belt portions 16. The girdle portion 18 prevents the brassière from riding up over the busts and retains it closely and firmly in position. The upper edge of the upper gore member extends over and confines the bust and has attached to it a strap 19, adapted to pass over the shoulders of the wearer and be attached to the side or belt members at its opposite ends. Preferably additional straps 20 may be attached to this main strap 19 from separated points at the upper edge of the brassière in order to aid in holding substantially the entire upper part of the bust supports of the garment in position over the form of the wearer.

I claim:

- 30 A brassière comprising bust supporting portions each including an upper elongated gore member having a downwardly curved lower edge, lower gore members for each upper gore member and having curved upper edges secured to the lower edges of the upper gore members, the lower gore members for each upper gore member having concaved confronting edges secured together and cooperating with the upper gore members to provide breast receiving pockets, a central spacer member secured to the gore members between the pockets and side members secured to the gore members.
